UNITED STATES PATENT OFFICE.

HARRY M. DALTON, OF CINCINNATI, OHIO, ASSIGNOR TO THE HALL'S SAFE COMPANY,
OF CINCINNATI, OHIO, A CORPORATION OF OHIO.

LOCKING MECHANISM FOR SAFES.

Application filed May 3, 1924. Serial No. 710,930.

My invention relates to locking mechanism for safes, and it is to be understood that the word safe is used to include vaults and other storage rooms or compartments 5 wherever the word safe is used in the description or claims.

It is the object of my invention to provide a new and improved locking mechanism for a safe, including a bar, which extends 10 lengthwise of a joint between the door and the wall of the door-opening, the bar comprising a plurality of parts extending lengthwise of the joint, and rotatable for placing the bar lengthwise in obstructing relation between the faces of the joint for locking the door in the door-opening, or for releasing the door; further, to provide a plurality of rotatable bars extending lengthwise in joints between the door and the wall 15 of the door-opening, and connected for rotation, whereby to locate the same into obstructing or unobstructing relations in said joints; further, to provide a rotatable bar extending lengthwise of a joint between the door and a wall of the door-opening, and means at the outside of the safe for rotating said bar, whereby to place the same in obstructing relation in the joint between the door and the wall; further, to lock said 20 bar in such obstructing relation; further, to provide connecting means removed from the outside of the safe between a plurality of rotatable locking-bars in the joints between the door and wall operable from the 25 outside of the safe; further, to provide a rotatable bar extending lengthwise of a joint between the door and wall, said bar comprising a plurality of parts respectively mounted on the door and on the wall and 30 arranged to be rotated and placed across said joint when the door is closed; further, to provide a rotatable bar as a bolt between the door and wall of the door-opening, said bar comprising a pair of parts, one of which 35 is mounted on the door and the other of which is mounted on the wall and arranged to coact when the door is closed for rotation of said parts to arrange the same across said joint to lock the door; and, further, to 40 provide means for limiting the rotation of said bar.

The invention will be further readily understood from the following description and claims, and from the drawings, in which 45 50 55 latter:

Fig. 1 is a front elevation of a safe, partly broken away, having my invention applied thereto, and partly in section to expose parts in the door and wall of the door-opening.

Fig. 2 is an inside elevation of a safe-door and wall, showing my invention applied thereto, the wall of the safe being partly broken away.

Fig. 3 is a horizontal cross-section of my improved device, taken on the irregular line 65 3—3, of Fig. 1, showing the safe-door closed and locked, and with the door-closing means partly broken away.

Fig. 4 is a similar view, showing the safe-door swung partly open, and with the cam 70 mechanism for closing the door removed.

Fig. 5 is a perspective view, partly broken away, showing one of the locking-bars.

Fig. 6 is a cross-section of a detail of 75 the corners of the door and wall, taken in the plane of the line 6—6, of Fig. 4.

Fig. 7 is an enlarged sectional detail, taken on the line 3—3, of Fig. 1, showing 80 the means for rotating the bar.

Fig. 8 is a vertical section of the operating means for the bars, taken in the plane of the line 8—8, of Fig. 3.

Fig. 9 is a vertical section of an exemplification of means for rotating an upper 85 bar, taken on the line 9—9, of Fig. 2.

Fig. 10 is a detail in vertical section, taken in the plane of the line 10—10, of Fig. 3.

Fig. 11 is a detail of the means for mounting the bar-sections, taken on the line 11—11, 90 of Fig. 2; and,

Fig. 12 is a cross-sectional detail, taken on the line 12—12, of Fig. 1, showing the means for forcing the door into the door-opening.

The body of the safe is shown broken away at 21, and is exemplified as the body of the so-called safe-vault. The door is exemplified at 22, and coacts with a door-opening 23, having a wall 24. Joints 25, 26, 27 and 28 are exemplified as located between the door and the wall. The joints are shown as stepped joints, comprising the steps 29, 30 and 31.

The door is exemplified as swinging on a compound hinge 35, arranged so that the door, during the final portion of its entrance into the door-opening, moves substantially perpendicular to that opening for proper 100 105 110

contact between the faces of the door and the wall of the door-opening forming the joints between them, and may be of any ordinary or usual construction and need not be further described for that reason.

The door is arranged to be forced into the door-opening for causing close joints between the door and wall, which may be accomplished by any ordinary or usual mechanism or pressure bar system for this purpose, and is exemplified as comprising shafts 37 having eccentrics 38 thereon and rotatable in suitable bearings 39 on the door. The shafts are rotatable by suitable gearing from a handle 40, the shafts, eccentrics and gearing being mounted on the door, and the eccentrics coacting with blocks 41 fixed to the wall, and having usual slots 42 in which the eccentrics are received for coacting with suitable shoulders 43 in said slots, for forcing the door into the wall of the door-opening.

A locking-bar 45 extends lengthwise of a joint between the door and wall, and is exemplified as comprising sections 46, 47, having coacting faces 48, 49, between them, extending lengthwise of the bar. The bar is exemplified as rotatable so as to place the same across the faces of the joint between the door and wall, and thereby lock the door in place, or for locating said faces coincident with the faces of the joint for unlocking the door. One or more of these bars may be provided. I have shown locking-bar 45 as at the swinging end of the door, a locking-bar 51 at the hinge joint of the door, a locking-bar 52 at the top of the door, and a locking-bar 53 at the bottom of the door. Each of these bars is exemplified as comprising a pair of sections parted lengthwise of the bar, the sections and faces therein having similar numerals applied thereto.

One of the sections of the bar extends lengthwise on the door and the other extends lengthwise on the wall, being preferably received in the door and in the wall. The door-section of the bar moves with the door, when the door is moved, and when the door is closed and locked both the sections extend across the joint between the wall and the door.

The bars are shown located in the inner step of the joints between the door and wall, and the sections are preferably provided with the coacting faces 48, 49, arranged to coact with each other when rotating the bar for locking the door or unlocking the same, and preferably respectively appearing as part of the face of the inner step on the door and part of the face of the inner step on the wall when the door is unlocked or open. The wall is provided with a recess 55 and the door is provided with a recess 56 extending lengthwise of the joint between the

same, in which the respective bar-sections are received.

The bar-sections and these recesses are preferably semi-cylindrical, the bar-sections being seated in the recesses, and, when the door is closed, unite to form a cylindrical bar located in a cylindrical recess in the joint, the bar-sections being so mounted as to permit rotation of the same in said recess in order preferably to maintain a close joint between the bar and the wall of its recess to maintain the door in closely locked relation, and to form a break in said joint to arrest any explosive or other device.

Each end of each bar-section is exemplified as provided with a recess 60, for forming an end-flange 61. The mating recesses, when the door is closed, form a bearing hole in which a journal-pin is received, the journal-pin being formed in sections, one section 62 of which is secured to the wall, as by a screw 63 received through a shank 64 extending from said section and located in a recess 65 in the wall. The other section 67 of the journal-pin is secured to the door, being provided with a shank 68 received in a recess 69 in the door, a screw 70 passing through the shank and being threaded into the door for securing the journal-section to the door.

This arrangement forms an annular groove in the wall and door when the door is closed, in which the end-flanges 61 formed at the ends of the respective bar-sections by the recesses 60 are received, for forming an annular flange at the end of the bar rotatable in the annular groove formed by the sections of the journal-pin. The rotation of one of said mating sections forces rotation of the other of said mating sections.

Means are provided for rotating the bar or bars, exemplified as comprising teeth 71, formed lengthwise in the bar-sections, and forming a gear about the axis of the bar, the tooth spaces being preferably sunk into the periphery of the bar.

A worm-gear 72 meshes with this gear on the bar 45, to rotate the same. The worm-gear is rotatable on a stud 74 extending from a plate 75 secured to the inner face of the door. The stud is shown fixed to the plate by having a reduced threaded end 76 pass through a hole in said plate and receiving a nut 77 thereover for clamping said stud to said plate between a shoulder 78 on said stud and said nut. The forward end of said stud is received in a bearing 79 in the door. (See Figs. 3 and 10.)

A gear 81 is fast with said worm-gear, and is meshed by a gear 82 secured to a spindle 83, (see Fig. 3), journaled in the door, and comprising a concial part 84 journaled in a bearing 85 in the door, to prevent driving the spindle inward of the door. This spindle carries a handle 86

for rotating the same. It is understood that the door may be of any suitable construction and the bearing 85 suitably located therein. While the door is shown solid, it 5 may, for instance, be built up of laminated steel and other plates.

Motion is also transmitted from said spindle to each of the other bars, when more than one of the bars is employed. For accomplishing this the spindle has a spiral-gear 91 fixed thereto, spaced from the rear plate 75 by a spacing collar 90. (See Figs. 2, 3 and 8.) This spiral-gear meshes with a spiral-gear 92 fixed to a cross-shaft 93, 15 journaled in bushings 94, 95, fixed to the rear plate of the door in bearings 96, 97. The cross-shaft has a spiral-gear 101 fixed thereto, which meshes with a spiral-gear 102, rotatable with a shaft 103, journaled in the 20 rear plate 75 and in a bearing 104 of the door, a spacing collar 105 being between the spiral-gear 102 and said rear plate. The construction is the same as that shown in Fig. 9 for rotating the upper locking-bar.

25 A gear 106 rotates with said stud and meshes with a gear 107, for rotating a worm-gear 108 shown as integral with said gear 107, and rotatable on a stud 109 fixed to the rear plate 75, by means of a threaded shank 110 extending from said stud and having a nut 111 received thereover, the construction 30 being the same as that shown in Fig. 10 for fixing the stud 74 in place. The end of said stud 109 is received in a bearing 112 in the door. The worm-gear 108 meshes with the teeth of the bar 51.

A block 115 is threaded to the cross-shaft on a screw-rod portion 116 of said cross-shaft, and is guided along the rear face of 40 the door, having slide-connection with the rear plate 75 of the door, to prevent relative rotation between said block and the door, whereby said block is moved axially on said cross-shaft. (See Figs. 2, 3 and 8.) 45 Endwise movement of the shaft is prevented by contact between the spiral-gears thereon and the bearings of said shaft. Movement of the block in one direction is limited by the bearing 96, and in the opposite direction by a bevel-gear 117 fixed to said cross-shaft, as by a pin 118, the bevel-gear serving as a stop-collar.

The endwise limits of movement of the block correspond to the limits of rotation 55 imparted to the rotatable locking-bars for locating the dividing plane between the bar-sections in the plane of the joint between the door and wall, at one limit of said movement, and locating said bar-sections cross-wise of said joint so that the parting plane 60 between said bar-sections is substantially at right angles to said joint at the other or locking limit of movement of the bars.

When at this latter limit of movement, 65 the block is arranged to have an obstruct-

ing part placed thereagainst to prevent re-rotation of the bars in release direction, instanced as the bolt 121 of a suitable combination lock 122, operable from the outside of the safe by a handle 123 on a suitable spindle 124, connecting the handle with the tumbler mechanism of the lock. This obstructing part may take the form of any other suitable obstructing mechanism or locking mechanism, as of a combination lock, 70 or time lock, or other suitable locking device. When the obstructing part is in obstructing relation, with the bar or bars rotated in their sockets with the door closed, the door is locked, and when the obstructing part is 75 removed from obstructing relation with the block, the bar mechanism may be operated to rotate the bars and unlock the door.

When an upper bar and a lower bar are employed, the same may be rotated by the 80 handle 86 by continuing the operative mechanism to said bars, instanced as accomplished by means of upright shafts 125, 126, journaled in bearings 127, 128, fixed to the rear plate 75 of the safe-door, and having 85 bevel-gears 129, 130, fixed thereto at their proximate ends, said bevel-gears meshing with the bevel-gear 117. Spiral-gears 134, 135, are fixed to the respective ends of said shafts, and mesh with spiral-gears 136, 137. 90

The spiral-gear 136 is fixed to a shaft 141 and has a spur-gear 142 thereon, fixed to rotate therewith. (See Fig. 9.) The shaft is rotatable in a bearing 143 in the plate 75 and in a bearing 144 in the door. It is 95 provided with a flange 145 which, with the gear 142 and a washer 146, fixes the shaft endwise in a recess 147 between the plate 75 and the door. A spacing-collar 148 is located between the spiral-gear and the 100 plate. The construction of the shaft 103 and the parts mounted thereon is similar to the shaft 141 and the parts mounted thereon.

The spur-gear 142 meshes with a spur-gear 151, which has a worm-gear 152 thereon. These combined gears rotate on a stud 153, which has a reduced threaded end 154 received through a hole in the plate 75. A nut 155 is threaded over this reduced threaded end for clamping the stud to said plate, the plate being located between the nut and a shoulder 156. The forward end of the stud is located in a bearing 157 of the door. The worm-wheel 152 meshes with the gear 71 on the locking-bar 52 for rotating the same.

Similar means, reversely placed, are provided for rotating the locking-bar 53, indicated by similar but primed reference numerals.

I have exemplified the means for rotating the locking-bars as mounted on the door, although I do not limit myself to such location of said rotating means, as said rotating 130

means may be mounted in the wall of the door-opening, and said locking-bars may be rotated from the outside of the same instead of from the inside of the same as exemplified.

In operation, when the door is open, as illustrated in Fig. 4, the sections of the locking-bar are respectively received in the wall of the door-opening and in the door, 10 the parting planes of said sections being preferably coincident with the faces of the joints between the wall and the door.

Swinging the door into closed position and manipulating the handle 40, forces the 15 door into the wall of the door-opening, and causes seating in the joints of the same, and also causes the sections of the locking-bars on the door to register with the sections of the locking-bars in the wall of the door-opening, 20 for coercive relation between the mating faces of said sections.

When now the handle 86 is turned, the 25 worm-wheels on the door, which mesh with the gears on the locking-bars, cause rotation of the locking-bars, the rotation of the sections of the locking-bars on the door being transmitted by contact between the coacting faces to the sections of the locking-bars in the wall of the door-opening, where- 30 by the sections of the locking-bars are arranged across the joints between the door and wall for locking the door, as shown in Fig. 3.

During such locking movement, the block 35 115 has axial movement imparted thereto along the screw-portion 116, for forming a space between said block and the bearing 96, whereupon, by manipulation of the combination lock, the bolt 121 is moved into 40 obstructing relation with said block, for maintaining the bolt-works in locked relation.

Rotation of the bars beyond the desired 45 angle of rotation is prevented by contact of the block 115 with the bearing 96, when the parting planes of the locking sections are coincident with the joints between the door and wall for unlocked relation of the door, the block 115 contacting the bevel-gear 117 when said bar-sections are located 50 in the locked relation, as shown in Fig. 3.

As an element of safety the spindle 83 is 55 preferably a thin spindle, which would be severed if force were applied to the handle 86 for rotating the same in excess of that ordinarily employed for rotating the locking-bars, in order to minimize or avoid the danger of burglarious rotation of said locking-bars.

60 My improved locking means is simple and effective, and provides a locking bolt extending lengthwise throughout substantially the entire length of the joint between the door and its wall.

65 In my improved device, further, the door-

faces of the joints are held in close impingement against the wall-faces of said joints throughout said joints, by substantial bars having close impingement with the walls of the recesses in the door and wall 70 in which said bars are located, forming uniting faces of substantial area throughout substantially the lengths of said joints, and resisting movements of said door in burglarious attempts, by means of the pressure 75 bar system or otherwise, for preventing the formation of sufficient space in the joints to permit introduction of explosive or other opening means.

Having thus fully described my invention, 80 what I claim as new, and desire to secure by Letters Patent, is:

1. In locking mechanism for a safe, the combination with a door and a wall of a door-opening, of a pluripart rotatable locking-bar having an axis of rotation extending lengthwise of a joint between said door and said wall, said locking-bar extending substantially throughout the length of said joint, the parts of said bar having a parting 90 plane between them extending lengthwise of said joint, means for rotating said bar for locating said plane coincident with said joint for unlocked relation of said door or crosswise of said joint for locked relation 95 of said door, and means for maintaining said locking-bar in said last-named relation.

2. In locking mechanism for a safe, the combination with a door and a wall of a door-opening, of a rotatable pluripart locking-bar extending lengthwise of a joint between said door and said wall substantially throughout the length of said joint and having an axis of rotation substantially in said joint, the parts of said bar located respectively in said door and in said wall for unlocked relation of said door and crosswise of said joint for locked relation of said door, each of said parts rotatable about said axis in said door and in said wall, and means 105 at the outside of said door for rotating said bar.

3. In locking means for a safe, the combination with a door and a wall of a door-opening, of a locking-bar in sections extending lengthwise of a joint between said door and said wall, one of said sections on said door and the other of said sections on said wall when said door is in unlocked relation, and said sections rotatable together for 115 extending into both said door and said wall, said sections provided with teeth, and means coacting with said teeth for rotating said sections.

4. In locking means for a safe, the combination with a door and a wall of a door-opening, of rotatable locking-bars extending lengthwise of joints between said door and said wall, operating means connecting said bars for combined rotations after said 125 130 135

door is closed, and means at the outside of the safe for operating said last-named means.

5. In locking means for a safe, the combination with a door and a wall of a door-opening, of rotatable locking-bars extending respectively lengthwise of joints between said door and said wall and having axes of rotation which extend respectively lengthwise of said joints, said respective bars comprising sections respectively normally on said door and on said wall, and connected rotating means having operative connections with said sections for rotating said bars whereby to selectively place said sections across said joints and at the respective sides of said joints by rotative movement of each of said sections.

6. In locking means for a safe, the combination with a door and a wall of a door-opening, of a pluri-part locking-bar extending lengthwise of the joint between said door and said wall, rotating means for rotating said locking-bar, and obstructing means for obstructing rotation of said rotating means when said locking-bar is in locked relation.

7. In locking means for a safe, the combination with a door and a wall of a door-opening, of a pluri-part locking bar extending lengthwise of the joint between said door and said wall, rotating means, means on the outer periphery of said pluri-part locking bar complementary to said rotating means for rotating said locking bar, and obstructing means for said rotating means to obstruct rotations of the same in both directions.

8. In locking means for a safe, the combination with a door and a wall of a door-opening having a joint between them, of a rotatable locking-bar comprising a plurality of sections, said rotatable locking-bar having an axis of rotation substantially parallel with said joint located substantially in the plane of said joint when said door is closed, the door-face of said joint provided with a recess in which one of said sections is located during unlocked relation of the door and the wall-face of said joint provided with a recess in which the other of said sections is located during unlocked relation of the door, and means for rotating said locking-bar on said axis whereby to rotate each of said sections in each of said recesses for placing said sections across said joint.

9. In locking means for a safe, the combination with a door and a wall of a door-opening having joints between them, of rotatable locking-bars respectively comprising a plurality of sections, the door-faces and the wall-faces of said joints respectively provided with uninterrupted recesses, said respective rotative sections located in said respective recesses when the door is open, and means for simultaneously rotating the

sections of said respective bars when said door is closed for placing said sections across said joints and locking said door.

10. In locking mechanism for a safe, the combination with a door and a wall of a door-opening, of a pluri-part rotatable locking-bar extending lengthwise of a joint between said door and said wall substantially throughout the length of said joint and provided with an axis of rotation substantially parallel with said joint located in substantially the plane of said joint when said door is closed, the door-face of said joint provided with a recess in which one of said sections is located during unlocked relation of the door and the wall-face of said joint provided with a recess in which the other of said sections is located during unlocked relation of the door, said sections provided with coacting joint-faces arranged for mutual pressure-contact throughout their areas by the closing movement of said door and prior to rotation of said locking-bar, and means for rotating said locking-bar during maintenance of said pressure contact throughout the areas of said faces on said axis for rotative movement of each of said sections in each of said recesses and placing said sections across said first-named joint.

11. In locking mechanism for a safe, the combination with a door and a wall of a door-opening, of a substantially cylindrical locking-bar divided into a pair of sections, each of substantially semi-cylindrical form, having a parting plane between them substantially coincident with the joint between said door and said wall, each of said sections provided at each end thereof with a substantially semi-cylindrical flange, said door and said wall respectively provided with recesses and semi-cylindrical grooves at the respective ends thereof, said flanges and said grooves respectively substantially meeting when said door is closed, for forming substantially angular guides on which to rotate said locking-bar-sections, for selectively placing said locking-bar-sections crosswise of said joint or with their parting planes substantially coincident with said joint, and means for rotating said bar-sections.

12. In locking mechanism for a safe, the combination with a door and a wall of a door-opening, of a substantially cylindrical locking-bar divided into a pair of sections, each of substantially semi-cylindrical form, having a parting plane between them substantially coincident with the joint between said door and said wall, each of said sections provided at each end thereof with a substantially semi-cylindrical flange, said door and said wall respectively provided with recesses and semi-cylindrical grooves at the

respective ends thereof, said flanges and said grooves respectively substantially meeting when said door is closed, for forming substantially annular guides on which to rotate said locking-bar sections, for selectively placing said locking-bar sections crosswise of said joint or with their parting planes substantially coincident with said joint, a gear on said locking-bar, and means 10 at the outside of the safe for rotating said gear.

13. In locking mechanism for a safe, the combination with a door and a wall of a door-opening, of rotatable locking-bars 15 respectively comprising sections extending lengthwise of joints between said door and said wall and having coacting faces which coact when the door is closed for combined rotation of the sections of said respective 20 bars, said respective bars provided with teeth, pinions meshing therewith, operating means connecting said pinions, and a locking means comprising an obstructing part for obstructing rotation of said bars.

14. In locking mechanism for a safe, the combination with a door and a wall of a door-opening having a joint between them, of a rotatable locking-bar comprising a section normally in said door and a section 30 normally in said wall when said door is open, said locking-bar having an axis of rotation extending lengthwise of said joint, with said sections extending substantially throughout the length of said joint, said 35 sections provided with coacting pressure contact-faces arranged for coactive pressure contact by the closing movement of said door, and means for rotating said sections after closure of said door for placing said 40 sections across said joint for locking said door.

15. In locking mechanism for a safe, the combination with a door and a wall of a door-opening, of a rotatable locking-bar extending lengthwise of a joint between said door and said wall and rotatable in said joint for locking the door in said wall, and means limiting rotation of said bar, said last-named means comprising a block, a 50 screw-part arranged to be rotated for axial movement between said block and said screw-part, and means to limit said axial movement.

16. In locking mechanism for a safe, the combination with a door and a wall of a door-opening, of a rotatable locking-bar extending lengthwise of a joint between said door and said wall and rotatable in said joint for locking the door in said wall, and means limiting rotation of said bar, said last-named means comprising a block, a screw-part arranged to be rotated for axial movement between said block and said screw-part, means to limit said axial movement, 60 and a locking means comprising an obstruct-

ing part arranged to be placed in obstructing relation for obstructing said axial movement.

17. In locking mechanism for a safe, the combination with a door and a wall of a door-opening, of a rotatable locking-bar comprising a section normally in said door and a section normally in said wall when said door is open, said sections extending lengthwise of the joint between said door and said wall, means for forcing said door into said door-opening for coactive positioning between said sections, said sections provided with teeth, and a worm coacting with said teeth for rotating said sections whereby to place them across said joint for locking said door.

18. In locking mechanism for a safe, the combination with a door and a wall of a door-opening, of a plurality of locking-bars in the joints between said door and said wall, each of said bars comprising a pair of sections substantially cylindrical in cross-section and extending lengthwise of said respective joints and having coactive faces between them the planes of which are substantially coincident with the planes of said joints when in unlocked relation, gearing on said door between said bars whereby to rotate said bars for locating said coacting planes crosswise of said joint, and locking means for said gearing.

19. In locking mechanism for a safe, the combination with a door and a wall of a door-opening having joints between them, of a plurality of rotatable locking-bars each comprising sections extending lengthwise of the joints in which said sections are respectively received, the bar-sections provided with teeth for rotating the same, gears on the inside of said door coacting with said teeth and comprising spiral gears, shafting means on which the same are mounted, a limiting block with which said shafting means has screw connection, and locking means for said limiting block.

20. In locking mechanism for a safe, the combination with a door and a wall of a door-opening having a plurality of joints between them, of locking-bars, each comprising mating sections, in said respective joints, said mating sections located respectively on said door and on said wall when said door is in unlocked relation, gears on said respective locking-bars, shafting means journaled on said door for said respective locking-bars at substantially right angles to the latter, and spiral gearing between said shafting means and said respective gears on said locking bars.

21. In locking mechanism for a safe, the combination with a door and a wall of a door-opening having a joint between them of a pluri-part rotatable locking-bar comprising sections respectively extending

lengthwise of said joint and having close bearing lengthwise of said joint in the respective coacting faces of said joint, each of said faces provided with a slot extending lengthwise of said faces, said sections located in said respective slots, each of said sections rotatable in each of said slots, and means

to cause said sections to be arranged across said joint to lock said door and maintain juxtaposition of said faces.

10

In testimony whereof, I have hereunto signed my name.

HARRY M. DALTON.
